Primary Examiner — Sandra Snapp*Assistant Examiner* — Ieisha Price(74) *Attorney, Agent, or Firm* — McGuireWoods LLP(57) **CLAIM**

I claim the ornamental design for a cordless hedge trimmer, as shown and described.

DESCRIPTION

FIG. 1 is a right perspective view of the cordless hedge trimmer;

FIG. 2 is a front view of the cordless hedge trimmer shown in FIG. 1;

FIG. 3 is a rear view of the cordless hedge trimmer shown in FIG. 1;

FIG. 4 is a left side view of the cordless hedge trimmer shown in FIG. 1;

FIG. 5 is a right side view of the cordless hedge trimmer shown in FIG. 1;

FIG. 6 is a top view of the cordless hedge trimmer shown in FIG. 1; and,

FIG. 7 is a bottom view of the cordless hedge trimmer shown in FIG. 1.

The subject matter shown in dashed lines, and any surfaces of the design not shown, including interior surfaces, form no part of the claimed invention.
